HIS ATTORNEY

UNITED STATES PATENT OFFICE

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY

VALVE FOR ROCK DRILLS

Application filed August 25, 1927. Serial No. 215,368.

This invention relates to fluid actuated rock drills, but more particularly to a valve for distributing pressure fluid to the percussive element of the rock drill.

5 The objects of the invention are to protect the valve chest against wear and to obtain a quick and positive action of the valve.

Other objects will be in part obvious and in part pointed out hereinafter.

10 In the drawings illustrating a practical application of the invention,

Figure 1 is a longitudinal elevation in section of a rock drill showing the valve in one extreme position, and

15 Figure 2 is a similar view showing the valve in the other extreme position.

Referring to the drawings, the invention is shown embodied in a rock drill having a cylinder A provided with a free exhaust port B.

20 Within the cylinder A is a reciprocating hammer piston C having a forward fluted extension or nose D adapted to deliver blows on a drill steel, only the shank E of which is indicated in the front end of the

25 drill.

A suitable closure for the front end of the cylinder A is provided in the form of a front cylinder washer F bored to receive slidably the nose D of the piston C. A back cylinder 30 washer G inserted in the rearward end of the cylinder A forms a closure for said rearward end and in this instance also serves as an abutment for one end of a rotation ratchet H which is centralized by the cylinder and

35 encircles a head J of the rifle bar K.

The parts so far described are shown merely for illustrative purposes and it is to be understood that the invention which will be hereinafter described in detail is not limited 40 in its application to any particular type of drill.

In accordance with the present invention a valve chest L is shown formed on the side of the cylinder A and has a straight cylindrical 45 bore O extending therethrough to form a valve chamber P. The ends of the bore O in this instance are sealed by plugs Q held in operative position by bolts R.

Pressure fluid for actuating the drill may 50 be admitted thereto through a connection S

in the valve chest L. From the connection S lead a pair of supply passages T and U for introducing pressure fluid at points rearwardly and forwardly respectively of the transverse median line of the valve chamber P.

The plugs Q in this instance also serve as guiding means for a distributing valve V which controls the admission of pressure fluid from the chamber P to the front and rearward ends of the cylinder through inlet passages W and X respectively, and which inlet passages are of larger cross sectional area than the supply passages T and U. Accordingly, the plugs Q are provided at their 60 inner ends with annular flanges Y having bores Z adapted to receive cylindrical end projections b of the valve. On the free ends of the annular flanges Y are ribs Y' which are spaced with respect to each other to form 65 slots c for admitting pressure fluid from the chamber P into the inlet passages W and X, said slots c being controlled by the projections b which slide on the ribs Y' and over the ends of which projections the pressure 70 fluid flows during its passage into the ends of the cylinder.

Intermediate the ends of the valve V is a flange d which reciprocates between the supply passages T and U and has end surfaces e and f which cooperate with the inner ends of the flanges Y for limiting the travel of the valve V. The end surfaces e and f are at all times exposed to pressure fluid, as is also the perimeter g of the flange which, 80 it will be noted, is spaced from the wall of the valve chamber P to permit constant restricted communication between the ends of the valve chamber.

The operation of the device is as follows: 85 Pressure fluid admitted into the connection S will pass through the supply passages T and U into the valve chamber P. With the valve in the position illustrated in Figure 90 1, such pressure fluid will flow over the rearward projection b and through the inlet passage X into the rearward end of the cylinder to actuate the piston C forwardly.

95 After the free exhaust port B is overrun by the piston C, the air in the front end of 100

the cylinder will be compressed. Such compression flowing through the inlet passage W will act against the front end of the valve, tending to throw the valve V rearwardly.

5 Shortly prior to the instant the blow of the hammer piston C is delivered to the drill steel E, the exhaust port B will be uncovered, thus causing an abrupt drop in pressure in the rearward end of the cylinder. Due to 10 this drop in pressure, the pressure in the rearward end of the valve chamber P will of course also drop somewhat below line pressure. With this condition obtaining, pressure fluid in the front end of the valve chamber P will flow over the perimeter of the flange d and create a suction on said flange which will assist the compression acting against the forward projection b to throw the valve V to its rearward extreme position.

20 Upon reversal of the valve V pressure fluid will flow over the forward projection b through the inlet passage W into the front end of the cylinder and actuate the piston C rearwardly. During the rearward stroke, as during the forward stroke of the piston C, compression will also be built up and such compression acting against the rearward projection b, together with the suction 30 created by the pressure fluid flowing over the flange d upon the occurrence of a drop in pressure forwardly of the flange d at the time the piston C uncovers the exhaust port B, will again throw the valve to its initial 35 position, thus completing the cycle of operations.

40 From the foregoing, it will be obvious that a valve constructed in accordance with the present invention is capable of rapid reciprocation. This is in part due to the almost complete absence of friction between the valve and the associated elements and in part to the manner in which the pressure fluid flowing over the valve flange d assists in 45 actuating the valve.

I claim:

1. In a fluid actuated rock drill, the combination of a cylinder and piston, a valve chest having a valve chamber, supply passages conveying pressure fluid into the valve chamber, inlet passages leading from the valve chamber to the cylinder and of larger area than the supply passages, a distributing valve in the valve chamber comprising cylindrical end projections controlling the inlet passages, said projections being intermittently exposed to compression from the cylinder for throwing the valve, and a flange on the valve reciprocable between the supply passages and constantly exposed at both ends to pressure fluid, said flange being of smaller diameter than the valve chamber to permit the flow of pressure fluid over the perimeter of the flange to create a suction thereon to 60 assist the compression in throwing the valve.

2. In a fluid actuated rock drill, the combination of a cylinder and piston, a valve chest having a valve chamber, inlet passages leading from the valve chamber to the cylinder, annular flanges in the ends of the valve chamber having bores communicable with the inlet passages, said flanges having ribs spaced to form slots for admitting pressure fluid into the bores, a distributing valve having end projections slideable on the ribs to control the slots, said projections being intermittently exposed to compression from the cylinder for throwing the valve, and a flange on the valve constantly exposed over its entire area to pressure fluid, the perimeter of said flange 70 being spaced from the wall of the valve chamber to permit the flow of pressure fluid over the flange from one side of the valve chamber into the other to create a suction on the flange for augmenting the compression to 75 80 85 90 95 100 105 110 115 120 125 130

3. In a fluid actuated rock drill, the combination of a cylinder and piston, a free exhaust port in the cylinder controlled by the piston, a valve chest having a valve chamber, inlet passages leading from the valve chamber to the cylinder, supply passages opening into the ends of the valve chamber, annular flanges in the ends of the valve chamber having bores communicable with the inlet passages, said flanges having ribs spaced to form slots therebetween for the passage of pressure fluid from the valve chamber to the bores, a distributing valve in the valve chamber comprising cylindrical end projections reciprocable on the ribs and controlling the inlet passages, said projections being intermittently exposed to compression for throwing the valve, and a flange constantly exposed at both ends to pressure fluid, said flange being of smaller diameter than the valve chamber to permit the flow of pressure fluid over the perimeter of the flange to create a suction thereon to assist in throwing the valve upon the occurrence of a drop in pressure in the 110 115 120 125 130

130 ends of the valve chamber due to the uncovering of the free exhaust port by the piston.

4. In a fluid actuated rock drill, the combination of a cylinder and a piston, a free exhaust port in the cylinder controlled by the piston, a valve chest having a valve chamber, inlet passages leading from the valve chamber to the cylinder, supply passages opening into the ends of the valve chamber, plugs forming closures for the ends of the valve chamber, annular flanges on the plugs having bores in communication with the inlet passages, ribs on the flanges and spaced to form slots for the admission of pressure fluid from the valve chamber into the bores, a distributing valve in the valve chamber having cylindrical end projections slideable on the ribs and controlling the slots, said projections being exposed to compression to assist in throwing the valve, and a flange on the valve constantly exposed

at both ends to pressure fluid, said flange being of smaller diameter than the valve chamber to permit the flow of pressure fluid over the perimeter of the flange and thus create a suction thereon to assist the compression in throwing the valve upon the occurrence of a drop in pressure in the ends of the valve chamber.

5 In testimony whereof I have signed this
specification.
